UNITED STATES PATENT OFFICE.

SAMUEL M. FRIEDE, OF ST. LOUIS, MISSOURI, ASSIGNOR OF ONE-HALF TO
JULIUS D. ABELES AND LEON GOLDMAN, BOTH OF SAME PLACE.

AUTOMATIC STREET OR STATION INDICATOR.

SPECIFICATION forming part of Letters Patent No. 391,699, dated October 23, 1888.

Application filed January 30, 1888. Serial No. 262,387. (No model.)

To all whom it may concern:

Be it known that I, SAMUEL M. FRIEDE, of the city of St. Louis, in the State of Missouri, have invented a certain new and useful Improvement in Automatic Street or Station Indicators, of which the following is a full, clear, and exact description, reference being had to the accompanying drawings, forming part of this specification, and in which—

10 Figure I is a sectional end view of a car with my indicator attached, showing the automatic action of the rocker-arm, under the influence of the riding buffer-pin attached to the post, by which the indicator is operated. Fig. II is 15 an enlarged perspective view of the rocker-arm, reactionary springs, and means of attachment to the car. Fig. III is an enlarged perspective view of the buffer-post and the riding buffer-pin, with the curvilinear inclined 20 track on which it rides. Fig. IV is an enlarged vertical section taken on line IV IV, Fig. V, showing the rolls that carry the indicator-scroll, the lamp that lights the scroll, also the alarm-bell. Fig. V is an enlarged horizontal 25 section taken on line V V, Fig. IV, showing the indicator as seen from beneath, the trip-lever, alarm-bell, and actuating-spring. Fig. VI is an enlarged top view of the buffer-pin, the inclined track on which it rides, the rocker-arm that it operates, and the reactionary 30 springs that bring back said arm to its normal position; and Fig. VII is an enlarged perspective view of the head of the buffer-post and the inclined curvilinear track on which the 35 riding buffer-pin travels. Fig. VIII is a detail of buffer-post with set-screws to clips.

This invention relates to devices for automatically indicating to passengers of railway-cars the next street or station at which the 40 train stops; and the invention consists in features of novelty, hereinafter fully described, and pointed out in the claims.

Referring to the drawings, in which similar figures of reference indicate like parts in all 45 the views, 1 represents a car to which my indicator-rolls are attached.

2 is the indicator-chamber, which incloses the spools 3 and 4, the indicating-scroll 5, that carries on its face the names 6 of the street or

station next ahead, the lamp 7, that illuminates the scroll after night, the coil-spring 8, its attached gearing, and the alarm-bell. One end of the coil-spring is secured to the pin 9, that is itself secured to the floor of the indicator-chamber, and the other end is secured to the 55 shaft 10, which has bearings 11 in the top and bottom casing of the indicator-frame.

A drive gear-wheel, 12, on the shaft 10 meshes into the sprocket or spur wheel 13, which is rigidly secured to the sleeve 14, that carries the spool 3, and is itself carried and has a loose bearing on the shaft 15, one end of which is provided with a screw-thread, 16, that engages in a corresponding thread, 17, in the upper casing of the indicating-chamber. 65 A thumb-knob, 18, at the lower end of said shaft provides the means for turning the same when it has been run through the sleeve and is made to engage in its screw-seat. The corresponding spool, 4, is seated on the sleeve 19, 70 which surrounds the shaft 20, to which it is rigidly secured by the pin 21, so as to give the spool a forced rotation with the shaft when it has been placed in position and the pin inserted. The ends 22 of the sleeve form shoulders that keep the ends of the shafts in their bearings 23 in the upper and under casing of the indicator-chamber. The lower end of said shaft has a square seat, 24, for a common 75 crank-handle to fit thereon when the scroll is 80 to be wound up.

25 represents the alarm-bell, which is suspended from a pendent rod, 26, that is secured to the tablet 27, which is fastened to the upper casing of the indicator-chamber. A spring-stem hammer, 28, is secured beneath the tablet outside the bell by a pivot-pin, 29, and a reactionary spiral spring, 30, is secured to the pivoted shaft of the hammer and at its other end to the tablet above the bell. A lug, 31, 90 on the upper disk of the spool 4 (when the spool is revolving as it pays out the scroll) strikes the trigger-arm 32 of the handle of the hammer, turns it on its pivot, and the reactionary spring, in conjunction with the vibrating spring-stem 33 of the hammer, causes its ball 34 to reiterately strike the bell. A pin, 35, in the tablet limits the reactionary move-

ment of the hammer, and so presents its continuous pressure against the bell under the influence of the spring. A lug, 31, is pivotally fastened to the upper disk of said spool by the 5 pin 36, and has a trigger-arm, 31, against which a spring, 38, presses to force the face of the lug outward past the periphery of the disk, so as to strike the trigger of the hammer-handle as it passes. A pin, 39, against which the 10 trigger-arm is projected by said spring, limits the overthrow of the catch lug 31. The said lug has a round back or outer edge, so as to enable it to ride under the trigger-arm of the bell-hammer without hinderance and to pass 15 any other obstruction when the spool, with its scroll and the actuating coil-spring 8, is being wound up by the crank on the shaft 20.

The indicating-scroll 5 is secured at its ends to the spools 3 and 4, so that as the spool 4 is 20 wound up it unwinds from spool 3, the gearing in connection with which winds up the coil-spring 8, and thus lays up the spring-power that automatically operates the indicator-scroll.

25 A pendent door, 40, hinged at 41 to the door-cap 42 above it, has an elongated opening in its center, in which a pane of glass, 43, is preferably inserted to keep the dust from the chamber. The name of the street or station next ensuing is thus plainly exhibited to the passengers through said opening, whether glazed or otherwise. As a pointer and to explain the index, the words "Next Station" or "Street" (relatively according to whether it 30 be a steam or street-railway car) are painted or otherwise placed on the left-hand of said window in the door.

44 represents a dog-pawl that is secured by the pivot-pin 45 to the lower disk of the spool 4. A trigger-arm, 46, on said pawl is engaged by a spring, 47, that is secured to the disk and forces said trigger-arm against the stay-pin 48. Said trigger-arm by its reverse pivotal action projects the dog-lip of the pawl beyond the periphery of the disk, so that it engages with the catch-hook of the trip-lever 49, which is rigidly held between the forks of the trigger-arm 50, with which it is pivoted by the pin 51 to the angle-brackets 52, that are secured to one end of the casing of the indicator-chamber above and below the slotted aperture 53, through which said trigger-lever works.

55 A reactionary spiral spring, 54, is secured to the trigger-arm of the trip-lever 49 and to a staple, 55, that projects from the end of the casing, and said spring reacts on the trip-lever after its trip and brings its catch-hook back into engagement with the dog-pawl to arrest 60 the rotary movement of the spool after a single circuit. A dog-cleat, 55½, on the lower disk of spool 4 arrests the rotation of the spool if for any cause the pawl 44 fails to catch the hook of the trip-lever 49.

65 The trigger-arm 50 is pivoted on the fork of the link 56 by the pin 57, and said link is pivoted to the crank-arm 58 by the pin 59. Said

crank-arm is rigidly secured to the inner section, 60, of the compound rocker-arm.

The rocker-arm is supported at its inner end 70 by the socket-bracket 61, which is secured to the inner side of the cupola of the car-roof and by the vertical journal-bracket 62, that is secured on top of the lower section of the arched roof of the car. An enlargement of the outer 75 end of the inner section of the rocker-arm forms a joint-head, 63, in the bifurcated end 64 of which the outer section, 65, of the rocker-arm is seated and connected by the pivot-pin 66.

A curved arm, 67, is seated in a slot, 68, in 80 the joint-head, in which it is rigidly secured. Twin spiral springs 69 are secured to the ends of the curved arm at one end and at the other to the perforated projecting lugs 70 a certain distance in advance from its pivoted connection on the outer section of the rocker-arm. This double reactionary spring attachment of the pivoted outer section of the rocker-arm allows it free lateral swing and return movement, as will be more particularly shown in 85 the operative description.

The outer section of the rocker-arm telescopes into an angle tube, 71, within the vertical section of which is also telescoped a pend- 95 ent rod, 72. A set-screw, 73, and a similar screw, 74, relatively set the horizontal and vertical length adjustment of the rocker-shaft.

75 represents the buffer-post, which is set alongside the track at a sufficient distance therefrom not to unduly interfere with the 100 passing trains, but sufficiently near for its riding buffer-pin to trip the rocker-shaft. Near the head of the post it is encircled by a collar-clip, 76, within the socket-lug 77 of which the foot of the buffer-pin is seated, and a sim- 105ilar collar-clip, 78, still nearer the head of the post, seats the upper end of the vertical section of said buffer-pin in the socket of its project- 110 ing lug 79, and both clips are relatively set on the post when adjusted to the right height by the set-screws 80 and 81. A flanged collar- 115 clip, 82, surmounts the last-named clip around the head of the post and is tightly secured thereto, when adjusted, by the set-screw 83, and carries riveted to its flanged side an in- 120 clined curvilinear trackway for use to be further disclosed in the description that now follows of the traveling buffer-pin.

84 represents the buffer-pin, which consists of a vertical rod, 85, that is seated in the sockets 125 of the lugs 77 and 79 of the clips 76 and 78, and is surmounted by the elbow 86, which connects it to the horizontal sleeve 87, that telescopes the adjustable contact-pin 88, that is set to its adjustment within the sleeve 87 by the screw 89, so as to be accommodated to the width of cars 130 traversing the track. 90 is a key-pin at the foot of the buffer-pin to keep it from lifting out of its seat.

91 represents a journal-box truck, in which 130 the telescopic sleeve 87 of the buffer-pin is seated and by it carried over the curvilinear inclines 92 of the reactionary track, whose rear bar, 93, is secured by bolts 94 to the flanged

wings 95 of the clip 82, that embraces the head of the post. The said truck-boxing 91, that carries the buffer pin, is provided with perforated pendent lugs 96, in the perforations of 5 which is secured the axle 97, that carries the track-wheel 98, which traverses the curvilinear inclines 92, and so the track, carries round the buffer-pin, when it contacts with the pendent-pin 72 on the rocker-bar of the car, and 10 after performing its functions, when the buffer-pin is released from the rocker-bar, the truck carries back the pin down the incline to its normal position.

The indicating devices, with their actuating 15 rocker-arms, &c., are preferably duplicated, so as to be located at each end of the car, as each end alternately becomes the forward end, and in consequence the end toward which the 20 seats of the passengers are faced. Buffer- posts are also correspondingly located in positions required to operate the rocker-bars when the train is running either way.

The operation of my invention is as follows: The buffer-posts are placed alongside the 25 track, (preferably on the right-hand side relatively to that on which the train is moving, to which the buffer-pin operates, although they may be placed on either or both sides.) The posts are preferably planted at points adjoining 30 the street or station the train has just left, so as at that point to change the indication from that of said street or station to that of the one next ensuing. Along single tracks the posts are placed on both sides of said track, 35 so as to operate on the indicator of trains coming from either direction. The post carries the compound riding buffer-pin 84, which is pivotally seated in the perforated lugs of adjustable clips that are seated on said post, and 40 are held by set-screws at an adjustable elevation suited to the height of the cars to be operated on. It will thus be seen that if there should be a change in the build of the rolling-stock the elevation of the buffer-pin on the 45 post can be raised or lowered in accordance with it and there secured by the set-screws. The buffer pin, besides being pivoted in the lugs of said clips in which it has both free rotary and vertical movements within certain limits, 50 also rides on the truck-bearer 91, whose wheel 98 traverses the curvilinear inclines 92 of the bracket-track, which is secured to the head of the post. It will be seen that the peculiar conformation of said track allows the buffer-pin to ride round when it strikes the rocker-arm, and so in conjunction with the rocking of said arm after having tripped the indicator 55 it disengages therefrom, and as it has run up the incline, it now, when liberated, runs down the same and returns to its normal position, 60 ready for reaction when the next train passes. The finger 88 is adjusted in the sleeve 87 and there secured by its set-screw, so as to accord with the pendent rod 72 of the rock-bar that 65 it actuates. The said pendent rod is adjusted to its right length in the sleeve 71 and secured there by its set-screw.

It will be seen that when the buffer-pin strikes the rocker-arm and is operating its trip on the indicator devices the forearm of 70 the said rocker-arm turns on its pivot 66 with a sufficient lateral movement, in conjunction with the other devices already noted, to allow it free escape from the buffer-pin. The reactionary springs 69 then return it to its normal 75 position ready for future action. The set-screw 73 is used to set the adjustment of the length of the forearm. When the rocker-arm is thus operated by the buffer-pin, its crank-arm 58, through its pivot-link, operates 80 the trigger-arm and its trip-lever to trip the dog-pawl 44, that then allows a single rotation of the spool 4 under the influence of the coil-spring, as hereinafter described.

The coil-spring 8, as described, through its 85 shaft 10 and geared connections with the shaft 15 of the spool 3, causes a rotary strain on said spool when wound up, and through the indicator-scroll, whose ends are secured to said spool and to spool 4 and wound around them, 90 there is provided a rotary strain also on the latter spool. It thus follows, as stated, that when the dog-pawl 44 is tripped, as described, the spools make a single rotation, when the pawl is again engaged by the trip-lever 49, and as the circumference of the lay on the spool, either when full or at the last lay of its uncoil, is sufficient for the length of scroll on which is recorded the name of the incoming street or station such name, when projected against the window of 95 the indicator-chamber by the rollers 99 and 100, around which the scroll passes, is plainly exhibited to the passengers in the car. A lamp 100 back of the scroll illuminates the legend after dark.

A pivoted projecting lug, 31, on the upper 105 disk of spool 4, (when the spool rotates,) as it passes, trips the hammer of the alarm-bell 25, the vibratory spring-stem of said hammer enforcing for a short period a reiterating striking of the bell, which calls the attention of the passengers to the change of name of the street or station presented by the indicator.

It will be seen that like slotted apertures, 110 53, to those shown on the right-hand side of the car are also shown on the left hand for the passage of the inner end of the rocker-arm, &c., when the actuating devices are required to be operated from the other side of the car. Then the buffer-posts, rocker arms, and other actuating devices will be located, or also located, 115 on the reverse side to that before stated. A single indicator at one end of the car may thus, if desired, be made to answer the required purpose, (by transposition,) when the 120 train is running in either direction.

When it is desired to reverse the position of the actuating devices of the indicator or remove the scroll and spools for repairs or any other purpose, said parts can be easily taken 125 out, after unscrewing the shaft 15 of the spool 3, (making use of knob 18 for that purpose,) withdrawing said shaft, and the removal of pin 21 and shaft 20 from within the sleeve of

spool 4, and then the spools and scroll can be removed without difficulty.

The words "Next Street" or "Station," as the case may be, which are shown on the door on the left hand of the indicator-window to call the passengers' attention to said indication, may be also placed on the other end of said window, so as to call attention thereto from the passengers on the other side of the car.

10 When the spring-coil is run out by the time the train has reached the end of the track, it is wound up again and the indicator-scroll reverse lapped around the spool 4 by the action of a hand-crank of usual construction, which 15 is fitted on the square stem 24 of the shaft 20, and when the one recording-indicator alone is used and it is desired to reverse it and its actuating devices at the end of the run it is easily accomplished after the withdrawal of the spool-shafts by the means described above.

101 is a small door within the door 40, which opens the way for the deposit of the hand-crank or other small tools when not in use.

I claim as my invention—

25 1. In a street and station indicator for railway-cars, the combination, with the indicator proper secured to the car, and its trigger trip-lever, of the rocker-arm projecting toward the side of the track from the car and the buffer-post 75, and compound buffer-pin 84, with its pivotal connections to said post, and said buffer-pin arranged to trip the rocker-bar, substantially as and for the purpose set forth.

35 2. In a street and station indicator for railway-cars, the combination, with the indicator proper secured to the car, and its trigger trip-lever, of the inner arm, 60, of the rocker-arm, the journal-bracket 62, that supports the same, the joint-head 63 with its curved arm 67 and 40 bifurcated end 64, the forearm of rocker pivoted in said head, and reactionary springs 69, to allow lateral movement to the rocker-arm, and the buffer-post, and compound buffer-pin 84, arranged to trip the rocker-bar when it 45 comes in contact with it, and by means of said bar operates the trigger-lever that trips the spring-actuated indicating device, substantially as described, and for the purpose set forth.

50 3. In a street and station indicator for railway-cars, the combination, with the indicator proper secured to the cars, and its trigger trip-lever, of the rocker-arm projecting toward the side of the track, the buffer-post 75, and 55 compound buffer-pin pivoted to said post, the truck 91, that carries the pin and truck-wheel 98, and inclined curvilinear track 92, on which said truck and its wheel runs, the buffer-pin arranged to trip the rocker-arm as the cars of 60 a train pass, and thereby trip the trigger-lever to allow a rotation of the indicator-spools under the tension of the coil-spring 8, and the consequent change of record on the scroll, substantially as and for the purpose set forth.

65 4. In a street and station-indicator for railway-cars, the combination, with the indicator proper secured to the car, and its trigger trip-

lever, of the compound rocker-arm consisting of the inner arm, 60, and fore or outer arm, 65, the pivotal joint of said arm that allows 70 lateral movement of the outer arm when tripped, and the reactionary springs and curved arm that enforce the return of said arm to its normal position, and the buffer-post and compound buffer-pin that trip said rocker-arm, and thereby the trigger-lever, that releases the indicator-spools, said spools and the indicator scroll they carry, and the coil-spring that actuates the spools when so released, substantially as and for the purpose set forth. 80

5. In a street and station indicator for railway-cars, the combination, with the indicator proper secured to the car, and its trigger trip-lever, of the compound pivoted and spring-jointed rocker-arm with adjustable angle-sleeve 71, the pendent contact-rod 72, and set-screws 73 and 74, that fasten the angle-sleeve to its adjustment, the buffer-post 75, and compound buffer-pin 84, that trips said rocker-arm, substantially as and for the purpose set forth. 90

6. In a street and station indicator for railway-cars, the combination, with the indicator proper and its trigger trip-lever, of the compound pivoted spring-jointed rocker-arm, the 95 buffer-posts 75, stationed at points alongside the track where the indicator is to be operated, the clips 76 and 78, that embrace said post, with lugs 77 and 79 on said clips, the vertical rod 85, pivoted in said lugs, elbow-joint 100 86, sleeve 87, and adjustable tapping-rod 88, the compound buffer-pin 84, that trips the aforesaid rocker-bar, and the set-screw 89, that fastens the tapping-rod 88 to its adjustment, the truck 91, that carries the buffer-pin, and 105 inclined tracks 92, secured to the flanged clip 82, that embraces the top of the post, substantially as and for the purpose set forth.

7. In a street and station indicator for railway-cars, the combination of the buffer-post, 110 the compound riding buffer-pin with adjustable tapping-rod pivoted to said post, the pivoted spring-jointed rocker-arm mounted on the car, which arm is tripped by the buffer-pin, and the trigger-lever that it trips, the dog-pawl 44, the spools and indicator-scroll 5 that they carry, the coil-spring 8, that through its geared connections operates the spools, window-glass 43, through which the record is shown, and indicator-chamber 2, in which the 120 spool-rolls are run, substantially as and for the purpose set forth.

8. In a street and station indicator for railway-cars, the combination of the buffer-post, the buffer-riding-pin pivoted to said post, 125 the pivoted spring-jointed rocker-arm that the buffer-pin trips, the trigger-lever 49, and its reactionary spring 54, the dog-pawl said trigger trips, the spools, the indicator-scroll they carry, and coil-spring and gearing that 130 actuates them, the screw-fastened shaft 15 and spool-sleeve or bobbin 14, in which it is seated, the pin-fastened shaft 20, and spool-sleeve 19, in which it is seated, and the square seat 24 on

shaft 20, for seating the hand-crank that turns the shaft and winds the spools and coil-spring, substantially as and for the purpose set forth.

9. In a street and station indicator for rail-way-cars, the indicator proper secured to the car, and its trigger trip-lever and dog-pawl, the spring-jointed rocker-arm mounted on said car, the buffer-post 75, and riding buffer-pin pivoted to said post and arranged to trip the rocker-arm at the points along the track where the indicator is actuated, the truck 91,

its track-wheel 98, and the curvilinear inclined tracks 92, on which the truck-wheel runs, arranged to lift the buffer-pin (while it trips the rocker-arm) to a vantage ground from which, 15 when released from the arm, it runs back on its truck to its normal position, substantially as and for the purpose set forth.

SAMUEL M. FRIEDE.
